UNITED STATES PATENT OFFICE.

CHARLES O. LORENZ, OF PORT ARTHUR, TEXAS.

DETECTOR FOR WIRELESS TELEGRAPHY.

1,159,969.

Specification of Letters Patent.

Patented Nov. 9, 1915.

Original application filed November 7, 1910, Serial No. 591,130. Divided and this application filed April 30, 1914. Serial No. 835,498.

To all whom it may concern:

Be it known that I, CHARLES O. LORENZ, a citizen of the United States, residing at Port Arthur, in the county of Jefferson and 5 State of Texas, have invented certain new and useful Improvements in Detectors for Wireless Telegraphy, of which the following is a specification.

This application is a division of my application filed November 7, 1910, Serial No. 591,130, and relates to a detector for use in high frequency electrical signaling systems, and particularly to the so-called minerals or substances employed for making electrical 15 contact as well as to the devices in which the minerals are mounted and through means of which they are manipulated to vary the contact.

The minerals employed and which I have 20 found in practice to give superior results are a combination of copper and sulfur known commercially as chalcocite, containing about 79.8% of copper and 20.2% of sulfur; also a combination of zinc and oxygen 25 known commercially as zinkite and consisting of about 80.3% of zinc and 19.7% of oxygen. These two minerals are mounted in the respective cups or holders in position to be brought into contact one with another.

30 The mechanism for mounting the minerals or contact substances in adjustable relation, contemplates the use of means for adjusting the two contacts to and from each other; resilient means through which 35 they are made to press one upon the other, with adjustment for varying such pressure at will and maintaining substantially the desired pressure notwithstanding other adjustments in the contacts; means for roughly 40 adjusting the contacts in the plane of their impingement, so that any part of one may be caused to contact with any part of the other; and means for effecting a fine adjustment in their plane of impingement, 45 whereby the range of variation in contact points is correspondingly increased.

The invention also contemplates a cut-out switch through which to shunt the detector with reference to the receiving circuit.

50 The invention will be fully understood upon reference to the accompanying drawings, in which—

Figures 1, 2 and 3 are, respectively, a top

plan view, a front elevation, and a side view of a detector constructed in accordance with 55 my invention.

1 represents a base having mounted thereon a block 2 carrying a fixed arm 3 and a pivotally mounted arm 4. The arms 3 and 4 carry the contacts, and in order that the pressure through which the contacts bear one upon the other may be varied at will, arm 4 is mounted upon a pivot 5 and provided at one end with a pressure spring 6 exerting its influence upon the arm through 60 means of a set screw 7 that may be adjusted at will. The arms 3 and 4 are provided with disks 8 and 9, respectively, adapted to be rotated upon their true axes; the disk 8 being carried by a shaft 10 having a rotating head 11 and being preferably 65 threaded so as to serve the combined purpose of rotating the disk 8 and moving said disk bodily in the direction of its axis. The disk 9 is mounted by means of a circumferential groove 12 receiving the forks 13 that are carried by the pivoted arm 4 and is thus made rotatable on the arm which carries it, though without bodily adjustment relatively to the arm. The disks 8 70 and 9 have eccentrically mounted in them, mineral cups 14 and 15, respectively; cup 14 being preferably supplied with chalcocite and the cup 15 being 75 preferably supplied with zinkite which may 80 be held in place by means of the set screw 16.

The cups 14 and 15 are held in place by means of the shanks or pins 17, 18, which adapt them to rotate upon their own axes; the shank 18 being also adjustable axially to 90 move cup 15 toward or away from the cup 14. After bringing the minerals into impingement by adjustment of the shaft 10 and the pin 18, they may be given any desired relative adjustment in the plane of impingement, and caused to bring any point on either of them into contact with any point on the other, through means of the orbital movement which each cup has by the rotation of the disk on which it is mounted, followed by a rotation of either or both cups on their own true axes. These adjustments do not effect material change in the pressure with which one bears against the other, because this is regulated by the spring 6 and 95 screw 7. This spring also permits of slight 100

axial movement in the shaft 10 and pin 18 incident to their rotation in effecting adjustments in the plane of impingement.

19 represents a switch arm pivoted at 20 and having electrical connection with the pivot 5 of the arm 4.

21 and 22 represent two contact pins adapted to be bridged by the switch arm 19.

23, 24 and 25 represent three binding posts, of which binding post 23 is connected to the contact pin 21 and is intended to receive an external wire from the inductance in the system, while binding post 24 is connected to contact 22 and is intended to receive a wire from one side of the condenser and receivers in the system, while binding post 25 is connected to the other side of the receivers and to the condenser. When the switch arm 19 is upon the contacts 21, 22, the detector is completely shunted from the receiving circuit.

While I have described certain minerals which I prefer to use because of superior results obtained thereby, and certain mechanism to be employed for holding the minerals in operative relation to each other, I desire it understood that I do not limit myself to the use of these features in combination, as either may be used independently of the other or in combination with some suitable substitute.

I claim:—

1. A detector comprising a body of chalco-cite electrically contacting with a conducting body.

2. A detector comprising a body of chalco-cite, and a body of zinkite electrically contacting therewith.

3. In a detector, a body comprising a cop-

per sulfid in electrical contact with a frag- 40
ment of zinkite.

4. In a detector, the combination of a pair of mineral bodies in electrical contact, one of said bodies comprising a copper sulfid.

5. In a receiver for electro-magnetic 45 waves, the combination of a pair of oppositely disposed cups, an adjusting rod secured to one of said cups and adapted to impart a rotatable and reciprocable movement thereto, a rotatable disk, wherein said rod is eccentrically mounted, whereby the cup and its adjusting rod may be rotated about the axis of said disk, and resiliently controlled means supporting said disk, and normally forcing said cup into proximity of the opposed cup. 50

6. In a receiver for electro-magnetic waves, the combination of a pair of oppositely disposed cups, an adjusting rod secured to one of said cups and adapted to 60
impart a rotatable and reciprocable movement thereto, a rotatable disk, wherein said rod is eccentrically mounted, whereby the cup and its adjusting rod may be rotated about the axis of said disk, resiliently controlled means supporting said disk, and normally forcing said cup into proximity of the opposed cup, and positive means for regulating the movement of the resiliently controlled means. 65

The foregoing specification signed at Washington, District of Columbia, this 11 day of November, 1913.

CHARLES O. LORENZ.

In presence of two witnesses:

HERVEY S. KNIGHT,

EDWIN S. CLARKSON.
